OLIVIER ANDRÉ GOBBÉ, OF JUMET, BELGIUM, ASSIGNOR TO EMILE GOBBÉ, OF JUMET, BELGIUM.

GAS-PRODUCER.

1,009,064.

Specification of Letters Patent. Patented Nov. 21, 1911.

Application filed May 5, 1909. Serial No. 494,139.

To all whom it may concern:

Be it known that I, OLIVIER ANDRÉ GOBBÉ, subject of the King of the Belgians, residing at Jumet, Belgium, have invented certain new and useful Improvements in Gas-
Producers; and I do hereby declare the following to be a full, clear, and exact description of the invention, such as will enable others skilled in the art to which it appertains to make and use the same.

The present invention relates to a gas producer serving for the distillation of coal or any other solid fuel for obtaining illuminating gas or heating gas, and coke. The distillation of the coal takes place with liberation of heat; if all the losses of heat produced in a gas producer, that is to say losses through the walls, are avoided, and if the gas and the coke are withdrawn cold the distillation will take place with a very small expenditure of fuel. In practice it is not possible to realize these conditions perfectly but they can be approached by providing the producer with the various means which form the object of the present invention.

In the accompanying drawings: Figure 1 is an axial section of a gas producer constructed in accordance with the invention. Fig. 2 is a cross section on the line A—B. Fig. 3 is a cross section on the line C—D. Fig. 4 is a cross section on the line E—F, and Fig. 5 is a vertical section of a modified form of the gas producer.

This gas producer presents the general form of a very high producer of the ordinary type.

The inner refractory jacket *a* of the producer is separated from the outer jacket *b* by a space *c* in which gas supplied from the producer through small holes *d* can be burned. The combustent air enters at the base of this annular space through openings *f* which can be closed as desired. The combustion which takes place in the space *c* heats the walls of the producer and the products of combustion escape through the chimney *g* in a relatively cool condition.

The coal is introduced through a hopper *h*, and holes *i* closed by small plugs enable the operation of the apparatus to be inspected and the large lumps of coke to be broken up from time to time in order to facilitate the passage of the gases and the descent of the fuel.

The ash pit is formed by a circular apron *l* the edges of which enter water seals. Counterweights *l* balance this apron in order to facilitate its operation.

The illuminating gas issues at the top 60 of the producer through the opening *m*, part of it being directed toward the scrubbers and the gas bell in passing through the conduit *n* provided with a valve *p'*, while the other part returns to the base of the producer in passing through the tube or conduit *o* provided with a valve *p*. The tar which condenses in the conduit *o* and in the set of tubes forming the conduit *n* is collected in a tank *q*.

The operation of the apparatus is as follows: For firing-up, wood and coal are burned at the base of the producer the ash pit being then open. During this time the products of combustion are allowed to escape through the chimney *g* or through the hopper, which is left open. In case the hopper is closed the rising products of combustion leave the producer through the openings *d*, whence they pass into the hollow wall and then to the chimney. During this firing up, the valves *p*, *p'* are closed. When the producer is filled with well kindled fuel, the ash pit and the hopper are closed. The valves *p* and *p'* are then opened so that a part of the relatively cold gas leaving the producer descends toward the ash pit through the conduit *o* while the other part proceeds directly into the conduit *n*, the scrubbers and the gas bell. The relatively 90 cold gas which reaches the ash pit absorbs the heat stored in the coke which is at the base of the producer and cools it in carrying its heat units upward into the zone of the reactions where other gases are produced. The mixture of return gas and gas produced passes through the layer of cold coal with which the apparatus is regularly charged from above and heats this coal before escaping in a relatively cold state 95 through the discharge outlet or passage *m*. An extractor (not shown in the drawing) sucks the gas produced and causes it to circulate in the conduit *n* and forces it into the gas bell after it has passed through the ordinary scrubbers. (The bell and the scrubbers are not shown in the drawing).

As the column of gas which rises in the producer has a mean temperature much higher than that of the gas contained in the 110

tube *o* descending toward the ash pit, the circulation of this gas returning to the producer takes place automatically. This circulation could, however, be facilitated by 5 means of a rotating fan sucking the gas at the upper part of the gas producer in order to force it back to the ash pit; the same result could be obtained in sending directly to the ash pit cold gas under pressure taken 10 from the gas bell. It is only necessary to regulate in a suitable manner the extent of aperture of the valve *p* to cause the velocity of this gaseous current to be such that all the heat contained in the red coke shall be 15 completely and methodically recuperated by the cold gas. In order to effect this recuperation thoroughly the gas must circulate slowly so that the greater part of the cold gas may have time to pass actually into the 20 interior of the lumps of coke which are sufficiently spongy to permit of this. If these conditions are appropriately fulfilled the apparatus will act as an actual heat unit filter and the gas will enter the reaction 25 zone at a temperature almost equal to that of the lumps of coke through which it has just passed. If on the other hand the gas should circulate too rapidly, the exchange of heat units would not be sufficient and the 30 gas would reach the distillation zone in too cold a state which would speedily cool the producer and bring the reactions to an end.

Cooling of the producer is avoided by constantly burning a small quantity of gas in 35 the double jacket *c* or by allowing air to enter through the ash pit every time it is opened for withdrawing a certain quantity of cold coke. Assuming that it is necessary to open the ash pit every hour in order to 40 extract cold coke and assuming that this operation occupies a few minutes only during this time, the air will burn a small portion of the coke which will reheat the distillation zone intermittently as is the case 45 in water gas producers. During this period, carbonic oxid gas is produced and is burned in the space *c* by opening the chimney *g* and the air holes *f* when the ash pit is opened. The duration of these periods of 50 internal reheating can be readily regulated in such a manner as to maintain the producer constantly at the desired temperature. The coke burned during this period of internal reheating and also the gas that is 55 allowed to burn in the double jacket of the producer, cannot amount to any considerable expenditure of fuel, because this producer produces cold gas and cold coke. It only loses heat units through its walls, which 60 can, however, be made very thick. It therefore realizes the conditions which must be obtained for distilling coal without expenditure of fuel or in expending but a very small quantity.

65 Fig. 5 shows a producer 1 in combination

with a smaller producer 2 in which a small quantity of coke is burned separately for the purpose of supplying the producer 1 with the heat units necessary to avoid cooling it. The upper part of this producer is 70 the same as in Fig. 1 with this difference that the gas intended to be returned to the ash pit is taken at 5 slightly below the upper level of the fresh coal, with the object of obtaining at this point a gas containing but 75 little hydrocarbon and a large quantity of hydrogen, in order to avoid the decomposition of the hydrocarbons during their passage through the red coke. The gas rich in hydrocarbons leaves the producer through 80 the opening 6 and proceeds directly to the scrubbers, the extractor and the gas bell. The passage of gas through the upright exterior outlet conduit 7^x is controlled by a counterweight valve 5^x, at the junction of 85 said conduit with the outlet passage 5. The ash pit differs in form from that represented in Fig. 1. The cold coke is removed through doors 3 which are closed in the same manner as retort heads. In order to facilitate the removal of the coke, pointed rods are passed through the holes 4 in such a manner as to constitute a false grate which is removed and replaced every time a charge 90 of coke is withdrawn. 95

The small producer 2 is charged with coke through the opening 7. It may be constructed in various ways.

1. If the illuminating power of the gas is of little importance, the poor gas is sent 100 directly from this producer into the interior of the producer 1. In order to do so it is only necessary to open the damper 8 which places the producer 2 in communication with the small holes 9. In this case all the other dampers of the producer 2 are closed and the door of the ash pit is opened to supply primary air to the producer 2. 105

2. If a rich gas of high illuminating power is required, the damper 10 is opened 110 in order to send the burned gases of the furnace of the producer 2 into the conduit 11. The other dampers are closed, but the ash pit is open and so is the chimney 12 in order to increase the draft in the producer furnace and draw into the double jacket 13 all the heat liberated during this period. 115

After operating with a forced draft for some ten minutes, the coke of the producer 120 2 will have become very hot and cold gas can be passed through it for absorbing its heat units and conveying them to the interior of the producer 1. In order to do so it is only necessary to close the ash pit and 125 place it in communication with the ash pit of the producer 1 by opening the damper 14. The damper 10 is then closed and the damper 8 opened so that the cold gas coming from the bottom of the producer 1 passes 130

into the producer 2, becomes highly heated there and enters the producer 1 through the small holes 9, thus re-heating this producer by internal heat but with external 5 combustion of the coke. The installation is run in this manner for about ten minutes likewise, then the producer 2 is re-heated as before by opening the door of the ash pit and the chimney 12 in order to draw the 10 heat into the annular space 13 and so on in succession, as is done in water gas producers. It would even be admissible to send steam through the opening 15 into the producer 2 during the period of internal heating of the producer 1, in order to produce 15 water gas in the producer 2 for mixing with the distillation gas of the producer 1, while at the same time heating the latter.

This gas producer is intended to be used 20 in place of furnaces for making coke and gas retorts for distillation of coal and any other solid fuel (wood, peat, brown coal, etc.) which will produce by distillation rich gas and coke.

25 I claim:

1. The combination, in a gas producer, of means for effecting a separation of the body of gas given off at the upper end of the producer, means for carrying downward a 30 part of such gas at the side of the producer and exteriorly thereof, and reintroducing it, without prior combustion, directly into the red coke in the lower part of the producer, and means to burn gas 35 from the producer in proximity to the wall of the latter, for reheating purposes.

2. The combination, in a gas producer having a hollow wall, of means for effecting a separation of the gas given off at the upper end of the producer, means for carrying 40 downward a part of such gas at the side of the producer exteriorly thereof and reintroducing it without prior combustion directly into the red coke in the lower part of the producer, means to admit gas to the producer wall for reheating purposes, and closures to admit air to the space in said wall.

3. The combination, in a gas producer having a hollow wall, of means for effecting 50 a separation of the body of gas given off at the upper end of the producer, means for carrying downward a part of such gas at

the side of the producer and exteriorly thereof and reintroducing it without prior combustion directly into the red coke in the 55 lower part of the producer, to carry the heat units from the lower part of the producer upward to the distillation zone, means for cutting off entirely the supply of air to the lower end of the producer, and means to 60 conduct gas into the producer wall for reheating purposes.

4. A gas producer having an outlet passage for the gas, an exterior return tube or conduit leading from said passage back to 65 the producer, an exterior off-take conduit leading from said passage to carry off a portion of the gas, and an independent valve in each of said conduits to control the amount of gas flowing into the same. 70

5. The combination, in a gas producer having a hollow wall, of a chimney communicating with the space in said wall at one side of the producer, a gas outlet at the opposite side of the producer, means to lead 75 a part of the gas from said outlet back beneath the body of coke in the producer, and means to burn a quantity of gas in said hollow wall.

6. The combination, in a gas producer 80 having a hollow wall with a horizontal series of openings leading from the interior of the producer into the space in said wall, of means to draw off the gas produced, means to re-introduce a part of such gas 85 into the producer beneath the body of coke therein; and means to admit air to the hollow wall to promote combustion of the gas issuing into the same when such gas is ignited to reheat the producer. 90

7. The combination, in a gas producer, of a gas outlet to carry off the gas produced, a conduit or tube communicating with said outlet and leading back to the producer, an off-take conduit also communicating with 95 said outlet, and a common collecting tank into which the gas in said conduits is passed to remove impurities.

In testimony whereof I affix my signature, in presence of two witnesses.

OLIVIER ANDRÉ GOBBE.
